(57) **CLAIM**

The ornamental design for a camera, as shown and described.

DESCRIPTION

FIG. 1 is a front perspective view of a camera according to the present invention;

FIG. 2 is a rear perspective view of the camera;

FIG. 3 is a top plan view of the camera;

FIG. 4 is a front elevation view of the camera;

FIG. 5 is a bottom plan view of the camera;

FIG. 6 is a rear elevation view of the camera;

FIG. 7 is a left side elevation view of the camera; and,

FIG. 8 is a right side elevation view of the camera.

The broken lines depict portions of the camera in which the

design is embodied and form no part of the claimed design.
